ALKYLATION OF AROMATIC AMINES

Paul Whittier Carleton, Pennsgrove, and Joseph Donald Woodward, Salem, N. J., assignors to E. I. du Pont de Nemours & Company, Wilmington, Del., a corporation of Delaware

No Drawing. Application December 12, 1931,
Serial No. 580,732

17 Claims. (Cl. 260—128)

This invention relates in general to the alkylation of aromatic amines, and particularly to the alkylation of primary aromatic amines when the alkyl groups to be introduced into the amine 5 contain more than one carbon atom. More particularly, the invention relates to the ethylation of aniline and its homologues.

It is well known that by a process of alkylation, alkyl radicals may be substituted for one or both 10 of the hydrogens in the amino group of a primary aromatic amine. With an alkyl radical such as the methyl group, this substitution takes place quite readily. For example, aniline when heated with methanol and a relatively small amount of 15 sulfuric acid, under elevated temperature and pressure may be converted substantially completely to dimethylaniline or mixtures thereof with monomethylaniline. However, if an alkyl alcohol of higher order than methyl is used, this 20 procedure is unsatisfactory because of side reactions and for other reasons. To a greater or less extent, other disadvantages have attended previously proposed methods for alkylating aromatic amines to a higher order than methyl. Thus, in 25 some processes heretofore proposed for ethylating aniline, mixtures of mono- and diethylaniline and unconverted aniline have been obtained. In order to be commercially feasible, such processes customarily involve removal or recovery of the 30 unconverted aniline, which adds to the cost of production and, in general, leaves much to be desired.

Our invention has as one of its objects a new and improved method of alkylating primary aromatic amines, particularly as regards alkylations 35 of aniline or its homologues to a higher order than methyl, whereby mixtures of the mono- and dialkyl substituted amines are obtained. A further object of the invention is the provision of a 40 flexible process for regulating the proportions of mono- and disubstituted amines produced. A still further object is the ethylation of aniline to produce substantially binary mixtures of mono- and diethylaniline by a method which is controllable to such an extent that a relatively small 45 change in the conditions of ethylation will cause a marked difference in the ratio of mono- and diethylaniline produced, and the amount of each product can be varied as needed. An additional 50 object of the invention is the provision of a method for ethylating primary aromatic amines which is better from the economic standpoint than any method previously proposed. Other objects and 55 advantages of the invention will be apparent by reference to the following description thereof.

In its broader aspects, the invention comprises producing mono- and dialkyl aromatic amines by reacting a primary aromatic amine with an alkyl alcohol, preferably of a higher order than methyl, and the corresponding alkyl chloride under elevated pressure and temperature. The resultant product contains an oily mixture of mono- and dialkyl aromatic amines, which may be recovered 5 in any suitable manner, for example, by making the reaction product alkaline, whereupon the oil separates from the remainder of the liquid and may be removed by means of a conical separator or by any other convenient method. The oily mixture may be used as such in certain chemical processes. Or, if desired, the mono- and dialkyl 10 amines may be separated from each other by any suitable means, for instance, by fractional distillation or by fractional crystallization of salts of the amines.

The invention may be well illustrated by the 20 ethylation of aniline. This is preferably accomplished by reacting aniline, ethyl alcohol, and ethyl chloride, under autogenous pressure and at an elevated temperature, while regulating the proportions of the reactants and more particularly the amount of ethyl chloride to produce a product containing a mixture of mono- and diethylaniline in desired ratios, substantially no unconverted aniline being present. The resultant mixture 25 may be recovered in any suitable manner and the two constituents separated or used as such without the difficulties and expense involved when a substantial amount of unconverted aniline is present. We have found this process to 30 be exceptionally advantageous on a plant scale 35 because of its flexibility.

While the invention is susceptible of considerable variation in the manner of its practical application, particularly as regards conditions of time, temperature, pressure and proportions of reactants used, the following examples will illustrate how it may be practised.

Example I

Aniline, ethyl chloride, and ethyl alcohol, in 45 proportions corresponding to 465 parts by weight of aniline, 208 parts of ethyl chloride and 250 parts of ethyl alcohol, were heated together in a closed vessel at 180–185° C. under autogenous pressure, 50 that is, the pressure produced by the reaction mixture, which in this case corresponded to about 175–225 pounds per square inch. After five hours heating, the charge was made alkaline and the oil layer separated by means of a conical separa- 55

tor. The oil contained approximately 60% monoethylaniline and 40% diethylaniline.

Example II

5 The reaction described in Example I was effected with 242 parts by weight of ethyl chloride instead of 208 parts, all other proportions of reactants and conditions of time and temperature remaining the same. The autogenous pressure in
10 this case was about 200-250 pounds per square inch. The oil was recovered as usual and analyzed approximately 35% monoethylaniline and 65% diethylaniline.

Example III

15 About 12.3 moles of ethyl alcohol, 5.0 moles of aniline and 4.0 moles of ethyl chloride were heated in an enamel-lined autoclave at 180-185° C. for five hours, the autogenous pressure of the reaction being about 300-360 pounds per square inch. The oil was recovered as described in Example I, and analyzed 12.5% monoethylaniline and 87.5% diethylaniline.

20 The following tabulations will form a basis for comparison of the various proportions of reactants and conditions of reaction described in the above examples.

	Example I	Example II	Example III
30 Time of heating (hrs.)	5	5	5
Temperature °C.	180-185	180-185	180-185
Pressure lbs./sq. in. (approximate)	175-225	200-250	300-360
35 Ratio moles ethyl alcohol per mole of aniline	1.09	1.09	2.46
Ratio moles of ethyl chloride per mole of aniline	0.645	0.75	0.80
Percent monoethylaniline in oil produced	60.0	35.0	12.5
Percent diethylaniline in oil produced	40.0	65.0	87.5

40 It will be seen in the above table that a change of about 0.10 moles of ethyl chloride per mole of aniline, all other conditions remaining the same approximately reverses the proportions of mono- and diethylaniline produced. Since the demand for each of the products varies from time to time, the advantage of being able to modify the process to meet the demand as it arises is obvious. This has heretofore been possible only to a much more limited extent.

45 We wish it to be understood that the above examples are not meant to limit the scope of the invention. Instead of aniline, we may alkylate the homologues thereof, e.g. the toluidines, (meta-toluidine, etc.) and xylidines, or any other primary aromatic amines such as the naphthylamines. The exact conditions of operation, of course, will depend upon the nature of the amine treated. In general, conditions subject to variation are the temperature, the time and the pressure of the reaction and the proportions of the reactants.

50 The temperature may vary within relatively wide limits, but, generally speaking, should be so regulated as to avoid ring alkylation at the higher temperatures and a low rate of alkylation at the lower temperatures. In ethylating aniline or its homologues, we prefer to employ temperatures within the range of 160-190° C. and preferably 180-185° C. For the ethylation of naphthylamines, temperatures below about 130° C. are preferable.

55 The time allowed for the reaction to take place appears to be a function of the temperature em-

ployed. If the temperature used is relatively low, a longer period of heating is required than in cases where the reaction is carried out at relatively high temperatures.

60 In practicing our invention we prefer to heat the reactants in a closed vessel so that the pressure of the reaction is the autogenous pressure produced by the reaction mixture. According to this method of procedure the pressure is largely a function of the temperature and the proportions of amine, alkyl alcohol, and alkyl chloride used. If desired, however, other sources of pressure may be employed such as, for example, the introduction of a compressed gas or vapor which is inert to the reactants or does not affect the reaction unfavorably. Elevated pressures tend to favor the production of alkyl aromatic amines by our process and pressures varying from slightly super-atmospheric to 1000 atmospheres are contemplated. As a general rule, it is preferable to 20 employ pressures within the range of about 10-100 atmospheres. In ethylating aniline pressures within the range of about 10-30 atmospheres have given especially desirable results.

65 The proportions of the various reactants employed to produce mono- and dialkyl substituted aromatic amines in accordance with our invention depend largely upon the ratio of mono- to dialkyl amines desired. Thus, within a certain range, other things being equal, a small increase in the amount of alkyl chloride present in the reaction mixture will increase the proportion of dialkylamine formed. In general, it is preferable that the amount of alkyl chloride used should fall within the range of about 0.6-1.0 mole per 35 mole of primary aromatic amine. The use of such small alkyl chloride concentrations is a distinctive feature of the invention and a decided advantage from the economic viewpoint.

70 The proportions of alkyl alcohol employed may vary within relatively wide limits but, generally speaking, should not be less than about one mole per mole of primary aromatic amine treated.

75 As previously indicated, the alkyl chloride used in effecting alkylations by our process should correspond to the alkyl alcohol employed, or vice versa. That is to say, the alkyl chloride and alkyl alcohol should contain the same number of carbon atoms similarly grouped. Otherwise, complex mixtures of alkylated amines may result. By alkyl we mean a radical derived from an acyclic hydrocarbon by the elimination of one atom of hydrogen, such as, for example, propyl, isopropyl, allyl, butyl, isobutyl, etc.

80 In describing our invention, we have referred to the production of mixed mono- and dialkyl aromatic amines, and particularly ethylated aniline and homologues thereof, which contain substantially no unconverted primary amine. In actual practise, it is difficult to determine the amount of primary aromatic amine in mixtures of mono- and dialkyl aromatic amines when less than about 1% of the primary amine is present. By substantially no unconverted primary aromatic amine, therefore, we mean less than about 1% by weight.

85 We have found that the present invention obviates many of the difficulties formerly attending large scale alkylations of a higher order than methyl, and particularly ethylations; that ethylated products of the character herein described can be produced more cheaply by our process than by any previously proposed method, and, in general, the invention represents an advancement of the art.

As many apparent and widely different embodiments of this invention may be made without departing from the spirit thereof, it is to be understood that we do not limit ourselves to the foregoing examples or description except as indicated in the following claims.

We claim:

1. In a process of producing mono- and dialkyl aromatic amines the step which comprises reacting a primary non-phenolic aromatic amine with an alkyl alcohol and the corresponding alkyl chloride under super-atmospheric pressure, the proportions of alkyl chloride used being within the range of 0.6 to 1.0 mole per mole of primary aromatic amine.

2. In a process of producing mono- and diethyl aromatic amines the step which comprises reacting a primary non-phenolic aromatic amine with ethyl alcohol and ethyl chloride under super-atmospheric pressure.

3. In a process of producing mono- and diethyl aromatic amines the step which comprises reacting a primary non-phenolic aromatic amine with ethyl alcohol and ethyl chloride under super-atmospheric pressure, the proportion of ethyl chloride used being within the range of 0.6 to 1.0 mole per mole of primary aromatic amine.

4. In a process of producing mono- and diethyl aromatic amines of the benzene series the step which comprises reacting a non-phenolic primary aromatic amine of the benzene series with ethyl alcohol and ethyl chloride under super-atmospheric pressure.

5. In a process of producing mono- and diethyl aniline the step which comprises reacting aniline with ethyl alcohol and ethyl chloride under super-atmospheric pressure.

6. In a process of producing mono- and diethyl aniline the step which comprises reacting aniline with ethyl alcohol and ethyl chloride under super-atmospheric pressure, the proportions of ethyl chloride used being within the range of 0.6 to 1.0 mole per mole of aniline.

7. The process of producing mono- and diethyl aniline which comprises reacting aniline with ethyl alcohol and ethyl chloride under super-atmospheric pressure and at a temperature within the range of about 160 to about 190° C.

8. The process of producing mono- and diethyl aniline which comprises reacting aniline with ethyl alcohol and 0.6 to 1.0 mole of ethyl chloride per mole of aniline, under super-atmospheric pressure and at a temperature within the range of about 160 to about 190° C.

9. The process of producing mono- and diethyl aniline which comprises reacting together in a closed vessel aniline, ethyl alcohol, and ethyl chloride in proportions corresponding to at least one mole of ethyl alcohol per mole of aniline, and 0.6 to 1.0 mole of ethyl chloride per mole of aniline, under autogenous pressure and at a temperature of 180 to 185° C.

10. The process of ethylating aniline which comprises reacting together aniline, ethyl alcohol, and ethyl chloride in proportions corresponding to at least one mole of ethyl alcohol per mole of aniline, and 0.6 to 1.0 mole of ethyl chloride per mole of aniline, under super-atmospheric pressure and at a temperature of 180 to 185° C., to produce a product containing a mixture of mono- and diethyl aniline but substantially no unconverted aniline, and separating said mixture of mono- and diethyl aniline from said product.

11. In a process of producing mono- and diethyl aniline the step which comprises reacting aniline with ethyl alcohol and ethyl chloride under a super-atmospheric pressure within the range of about 10 to about 30 atmospheres.

12. In a process involving replacing by an alkyl radical the hydrogen of an amino group of a non-phenolic aromatic amine, the step which comprises reacting said aromatic amine with an alkyl alcohol and the corresponding alkyl chloride under super-atmospheric pressure.

13. In a process involving replacing by an alkyl radical the hydrogen of an amino group of a non-phenolic aromatic amine which may contain alkyl substituents in the aromatic ring, the step which comprises reacting said aromatic amine with an alkyl alcohol and the corresponding alkyl chloride under super-atmospheric pressure.

14. In a process involving replacing by an alkyl radical the hydrogen of an amino group of an aromatic amine selected from the group consisting of aniline and homologues thereof, the step which comprises reacting said aromatic amine with an alkyl alcohol and the corresponding alkyl chloride under super-atmospheric pressure.

15. In a process involving replacing by an alkyl radical the hydrogen of an amino group of a non-phenolic aromatic amine which may contain alkyl substituents in the aromatic ring, the step which comprises heating said aromatic amine with an alkyl alcohol and the corresponding alkyl chloride under super-atmospheric pressure at an alkylation temperature below that giving rise to substantial ring alkylation of the amine.

16. In a process involving replacing by an alkyl radical the hydrogen of an amino group of a non-phenolic naphthyl amine, the step which comprises reacting the naphthyl amine with an alkyl alcohol and the corresponding alkyl chloride under super-atmospheric pressure.

17. In a process involving replacing by an alkyl radical the hydrogen of an amino group of a non-phenolic naphthyl amine, the step which comprises reacting the naphthyl amine with ethyl alcohol and ethyl chloride under super-atmospheric pressure.
